FOREIGN PATENT DOCUMENTS

JP D1356994 3/2009

Primary Examiner—Daniel D Bui(74) *Attorney, Agent, or Firm*—Rankin, Hill & Clark LLP(57) **CLAIM**

The ornamental design for a electrical connector, as shown and described.

DESCRIPTION

FIG. 1 is a front, right side, and top perspective view of an electrical connector in accordance with our new design;

FIG. 2 is a rear, right side, and bottom perspective view thereof;

FIG. 3 is a front elevational view thereof;

FIG. 4 is a rear elevational view thereof;

FIG. 5 is a left side view thereof, a right side view being a mirror image thereof;

FIG. 6 is a top plan view thereof;

FIG. 7 is a bottom plan view thereof; and,

FIG. 8 is a cross-sectional view thereof, taken along line 8—8 of FIG. 3.
